UNITED STATES PATENT OFFICE

2,671,595

CHICK BOX CLEAT

Andrew E. Miller, Fort Lauderdale, Fla., assignor
to Alton Box Board Company, Alton, Ill., a corporation of Delaware

Application September 28, 1951, Serial No. 248,821

2 Claims. (Cl. 229—6)

1

This invention relates generally to baby chick boxes, and particularly to a lid for spacing cleat arrangement for such boxes.

In the shipping of baby chicks, it is customary to utilize corrugated paper board boxes, which are provided with ventilating openings in the sides and lid, and which, where a plurality of packages are shipped concurrently, are provided with spacing cleats, so arranged as to prevent the blocking of the ventilating openings in the lid by the stacking of another similar package thereon during transportation.

Such spacing cleats, and the arrangements for affixing them to the chick boxes, have heretofore been provided in the form of wooden blocks, which are secured to the lids of the chick boxes. In view of the fact that frequently a limited number of boxes of baby chicks may be transported under circumstances such that blocking of the ventilating openings in the lids will not occur, it is desirable to provide a lid and cleat arrangement whereby the lid may be utilized with or without such cleats, and whereby the cleats, when desired, may be applied with facility and without requiring the use of tools.

It is therefore an object of the present invention to provide a chick box lid so constructed and arranged as to releasably receive spacing cleats, and to permit of their ready application.

Another object of the invention is to provide an improved cleat.

Other objects will become apparent to those skilled in the art in the light of the following description and accompanying drawing.

In accordance with this invention the lid of a chick box is provided with I-slots, each of which defines a pair of flaps. These flaps, when bent down, provide an opening in the lid. The opening so provided is of a width sufficient to allow the passage of a depending tenon on a spacing cleat but its length is such that the body of the cleat will not pass through. The spacing cleat is T-shaped in side elevation, the tenon, extending length-wise of the cleat forming the foreshortened stem of the T. The depending tenon is inverted T-shaped in cross-section to provide a groove below the spacing cleat and above the transverse element of the tenon on either side. The flaps and the tenon are so proportioned that when the tenon is inserted the flaps spring into the groove below the spacing cleat to lock the cleat in position. At the same time the flaps substantially close the opening when the cleat is not employed.

In the drawings:

Figure 1 is a fragmentary view in perspective

2

of a chick box having a lid and cleat arrangement constructed in accordance with the present invention;

Figure 2 is a fragmentary plan view of the chick box shown in Figure 1 with one of the cleats removed;

Figure 3 is a perspective view of a cleat in accordance with one embodiment of this invention;

Figure 4 is a sectional view taken along the line 4—4 of Figure 2;

Figure 5 is a sectional view of a cleat and lid showing the cleat at the beginning of its insertion within the opening;

Figure 6 is a sectional view of a cleat and lid showing the cleat partly inserted within an opening;

Figure 7 is a sectional view taken along the line 7—7 showing the cleat in its fully inserted and locked position; and

Figure 8 is a perspective view from beneath the lid showing a cleat in its fully inserted and locked position.

Referring now to the drawing a conventional chick box 1 having ventilating openings 2 in its sides and ends is provided with a lid 3. In the embodiment shown, the lid 3 is provided at its corners with a spacing cleat having a body portion 4 and a tenon including a head 5 and a neck 6 depending from the body portion 4. The cleat is shown in detail in Figure 3. As clearly appears from Figure 3, the tenon has a long horizontal dimension. The neck 6 and the head 5 are produced by grooves running lengthwise along each of opposite long sides of the tenon, giving the tenon in cross section the shape of an inverted T. Such a cleat may be formed by laminating several thicknesses of corrugated paper board, preferably arranged so that the corrugations 7 extend height-wise. The laminae are adhesively secured to one another and, as shown in the drawing, are coextensive.

In order to provide for the ready reception and positive locking of the spacing cleats, the lid 3 is provided with I-slots 10, the stem slot 11 of which is slightly longer than the depending tenon of the cleat and the transverse slots 12 of which are slightly longer than the width of the tenon head 5. In the embodiment shown score lines 14 on the underside of the lid 3 extend between the ends of the transverse slots 12. Each I-slot 10 with score lines 14 defines a pair of flaps 15.

To secure a cleat to a chick box lid provided with I-slots in accordance with this invention, the head 5 of the tenon need only be positioned

squarely between the transverse slots 12 and the cleat pushed down as shown in Figures 5, 6 and 7. The flaps 15 open along the score lines 14 until the head 5 has passed beyond the lower edges of the flaps, when the flaps spring back against the neck 6 to lock the cleat against upward displacement from the opening. In this position, the flaps slope downwardly to form in effect a diagonal brace against the stem and the upper face of the head 5. The lower face of the cleat body 4 engages the lid beyond the transverse slots 12 so that the cleat cannot be pushed completely through the opening. The cleat is maintained against longitudinal displacement by the engagement of the neck 6 with the edges of the lid defined by transverse slots 12 and against turning and lateral displacement by the flaps 15 bearing against both the stem 6 and the upper face of the head 5 of the tenon.

The openings are preferably arranged so that when the cleat is in its final locked position at the corner areas, it overlies the vertical side wall members of box 1, so that at least a triangular section of each corner cleat projects beyond the side wall of the box as shown at 20 in Figure 1. In this position the vertical load on the cleat is transmitted directly to the side walls of the box, and it is important to arrange the cleat so that, for its full width, the vertical support of the side walls is provided.

A chick box is generally provided with cross-dividers which intersect at the center of the box. If a center cleat is used, the top edges of these cross-dividers are preferably cut out just sufficient to accommodate the tenon of the cleat below the surface of the lid, and so that the bottom face of the tenon head 5 may rest on the upper margins of the cross-dividers, thereby providing support for vertical loads applied across the center.

It can be seen that various modifications of this invention are possible without departing from the spirit thereof. For example, the width of the tenon head 5 may be made less than the width of the cleat body 4 so that the cleat body is prevented from passing through the opening into which the tenon is inserted by the underside of the cleat body's bearing on the lid beyond the width of the opening as well as beyond the length of the opening. In such a construction the tenon can be made of equal length with the body, in which event only the overhanging of the body beyond the width of the opening will be effective to prevent the body's passage through the opening. Other variations within the scope of the

appended claims will be apparent to those skilled in the art in the light of the foregoing description.

Thus it can be seen that the invention accomplishes its objects, and provides a convenient and economical mode of connecting spacing cleats to the lid of a chick box, or utilizing the lid without such spacing cleats, as is desired.

Having thus described my invention what is claimed and desired to be secured by Letters 10 Patent is:

1. In combination with the lid of a chick box, said lid being provided with a plurality of I-slots each adjacent a corner, each of said I-slots defining a pair of flaps and providing an opening in 15 said lid; a plurality of cleats each associated with an opening provided by an I-slot, each cleat having a body and a tenon depending from said body and having a long horizontal dimension, said tenon having on each of opposite long sides a 20 groove extending lengthwise of said tenon, giving the tenon in cross section the shape of an inverted T with a head and a neck, said tenon being mounted in said opening, being smaller than said opening and shaped to pass therethrough, each of 25 the flaps of said I-slot sloping downwardly and extending within one of the grooves in said tenon and engaging the neck and upper face of the head of the tenon to lock the cleat against upward displacement from the opening, the body of the cleat 30 being larger than the said opening in a horizontal dimension to lock the cleat against downward displacement through said opening.

2. The combination of claim 1 wherein the cleat is composed of a multiplicity of coextensive 35 and adhesively secured laminae of corrugated paperboard, the corrugations of said paperboard being oriented heightwise of said cleat, the grooves in the tenon of said cleat extending transversely of said corrugations.

40 ANDREW E. MILLER.
